UNITED STATES PATENT OFFICE

127,950

DESIGN FOR A CASING FOR SOUND APPARATUS

David C. Rockola, Chicago, Ill., assignor to Rock-Ola Manufacturing Corporation, Chicago, Ill., a corporation of Delaware

Application February 5, 1941, Serial No. 98,749

Term of patent 3½ years

To all whom it may concern:

Be it known that I, David C. Rockola, a citizen of the United States, residing at Chicago, in the county of Cook and State of Illinois, have invented a new, original, and ornamental Design for a Casing for Sound Apparatus, of which the following is a specification, reference being had to the accompanying drawing, forming a part thereof.

Fig. 1 is a perspective view of a casing for sound apparatus showing my new design; and

Fig. 2 is a plan view of the casing shown in Fig. 1.

The grille of the design which appears near the base of the casing extends around the other two sides of the casing which do not appear in Fig. 1 of the drawing.

I claim:

The ornamental design for a casing for sound apparatus, substantially as shown and described.

DAVID C. ROCKOLA.
